ALIGNING DEVICE FOR WELL GRAPPLERS

Carl A. Anderson, Laverne, Okla., assignor of
one-third to Bruce L. Parker, Pampa, Tex.

Application December 13, 1950, Serial No. 200,512

10 Claims. (Cl. 294—86)

1

This invention relates to new and useful improvements in fishing tools and more particularly relates to means for engaging and urging objects into alignment with the fishing tool so as to be engaged readily thereby.

The primary object of this invention is to position objects that are inclined or laterally disposed to one side of the axis of the bore of a well in alignment with the axis of the bore of the well so as to be readily engaged by fishing tool.

Another important object of this invention is to provide means for use with rotary type fishing tools, which means will, in response to rotary motion, extend laterally from the axis of rotary motion to engage an object and move the same towards the axis of rotation.

Still another important object of this invention is to provide an aligning device of this character, which may be quickly and easily coupled to various types of fishing tools, and which itself may be efficaciously modified to meet various conditions, such as different size cave-in or cavity dimension in which an object may be located.

Yet another important object of this invention is to provide a device which includes a shell having means at its lower end to gather in an object so as to be received in the lower end of the shell as the same is lowered, and which shell carries means for securely engaging an object at its upper end, and which shell carries means disposed intermediate the other means for aligning the object with the axis of the shell upon descent of the latter about the object.

A meritorious feature of the present invention resides in the arcuate wing pivoted to the lower end of the shell, such wing being movable from a retracted position adjacent the periphery of the shell to an extended position outwardly from the shell, in which extended position the wing serves upon rotation of the shell to guide an object to a position within the shell. In addition, the wing is pivoted to the shell in such a manner that rotary motion of the latter causes the wing to move to its extended position by centrifugal force.

Another important feature of the present invention resides in the lower end of the shell being cut away adjacent the arcuate wing so that an object may readily move to a position within the shell as guided by the wing.

Still another important feature of the present invention resides in the transverse wall in the shell that has a concaved lower surface and a central opening therethrough for aligning an object with the central axis of the shell upon detent of the latter about the object.

2

Yet another important feature of the present invention resides in the provision of object engaging means at the upper end of the shell in axial alignment with the opening in the transverse wall.

A final important feature of the present invention to be specifically enumerated herein resides in the coupling member that serves a two-fold function of providing a connection between the 10 aligning device and the lower end of the string of tools that normally support the conventional fishing tool, and also which provides a housing for the object engaging means used in the present invention, it being noted that the object engaging means are carried by the coupling member so that upon simply changing coupling members having different types of object engaging means, the same aligning device can be used.

These, together with various ancillary objects 20 and features of the invention which will become apparent as the following description proceeds, are attained by the present invention, a preferred embodiment of which has been illustrated by way of example only in the accompanying drawings, 25 wherein:

Figure 1 is a side elevational view of the present invention, showing the same in use at the bottom of a well for aligning a section of pipe, and being carried at the lower end of a string of tools;

Figure 2 is another side elevational view similar 30 to Figure 1; however, this view showing the section of pipe as having been moved to a position in alignment with the central axis of the shell;

Figure 3 is a central vertical sectional view of the present invention taken upon an enlarged 35 scale, this view being taken on the plane of the broken section line 3—3 of Figure 5;

Figures 4 and 5 are both horizontal sectional 40 views taken on the plane of the section line 5—5 in Figure 3, Figure 4 showing the wings in their retracted positions, and Figure 5 showing the wings in their extended positions for engaging an object;

Figure 6 shows a modified form of the invention 45 differing from the form of the invention illustrated in Figures 1-5 by having a single wing construction; and,

Figure 7 is a detail vertical sectional view of a 50 modified form of object engaging means from those shown in Figure 3.

Reference is now made more specifically to the accompanying drawings, wherein like numerals designate similar parts throughout the various views. With attention first directed to the form 55 of the invention illustrated in Figures 1-5, there

is designated generally at 10 the bore of a well, at the lower end of which there is an enlarged cavity 12 in which is disposed for illustrative purposes an elongated object 14 that is desired to be removed from the well. For removing the object 14 from the well, there is suitably secured to the lower end of a string of tools 16 a device designated generally at 18 that forms the subject matter of the present invention.

The device 18 comprises a tubular shell 20 having pivoted to its lower end a pair of wings 22. Each of the wings 22 is pivoted to the shell 20 by means of a pair of bosses 22' and 24 formed on the innerside of the shell, such bosses having aligned apertures 26 therethrough. A slot 28 is provided in the shell 20 which extends between the bosses 22' and 24, in which slot 28 is disposed and enlarged portion 30 of the wing having an aperture 32 extending therethrough. A pivot pin 34 extends through the apertures 26 and 32, and is removably retained in the apertures by means of a counter-pin 36 extending through the boss 22' and the pin 34, the arrangement being such that the wings 22 may be readily removed from the shell 20 for replacement when worn, or for replacement by wings of different sizes when needed for a particular job. It will be noted that the wings 22 are pivoted to the shell 20 about axes that are substantially tangential to the shell and which axes are inclined both to the vertical and to the horizontal plane, so that the arcuate outer end portions 38 of the wings 22 extend downwardly from the pivotal connection of the wings to the shell. It will be further noted that the arrangement of the wings and the shell is such that upon rotation of the shell about its longitudinal axis will tend to urge the wings 22 from the retracted position, shown in Figure 4, to the extended position, shown in Figure 5.

As it will be appreciated, the wings 22 are for the purpose of extending outwardly from the shell, engaging an object such as that indicated at 14 and for directing the latter into the interior of the shell 20 upon rotation of the latter in a clockwise direction as shown in Figure 5. In order to facilitate the entry of the object 14 into the interior of the shell 20, the lower edge of the latter is cut away as at 40 rotationally in advance of the wings 22.

While the wings 22 serve the purpose of moving an object so that its upper end is received within the shell 20, it is desired that the object 14 be aligned with the axis of the shell 20, and for this purpose aligning means is provided which takes the form of a transverse wall 42 secured within the shell 20 which has a concaved lower surface and a central aligning opening 44, it being readily apparent that upon lowering of the shell 20 about an elongated object, such as that indicated at 14, the upper end of the object 14 will engage the concaved lower surface of the wall 42 so as to be moved to a position to pass through the central opening 44, thereby being aligned with the axis of the shell 20.

Threaded as at 46 upon the upper end of the shell 20 is a coupling member 48 which has a reduced upper end 50 that is internally threaded at 52 for detachable engagement with the lower end of the string of tools 16.

Means is disposed within the hollow coupling member 48 in alignment with the axis of the shell 20 for engaging the upper end of the object 14, so that the latter may be removed from the well. In the form of the invention shown in Figures 1-5, such means comprise a depending ta-

pered tubular member 54 integral with the coupling member 48, which has disposed therein a pair of complementary slip jaws 56 having serrated inner surfaces. It will be understood that when an object such as that indicated at 14 is extended upwardly through the tubular member 54, the jaws 56 will rise and spread apart to receive the object 14 therebetween; however, lowering of the object 14 will be prevented by the jaws 56 moving downwardly to wedge tightly thereabout to grip the same.

In the form of the invention shown in Figure 6, the shell and coupling member are shown as being of integral construction that is designated generally at 58. In addition, this form of the invention utilizes a single arcuate wing 60 that is pivotally connected to the combined shell and coupling member construction 58 as at 62. Since this modified form of the invention utilizes a single wing, this construction also uses only a single cutout portion 64, it being noted that the cutout portion 64 may be much larger than that shown in the other form of the invention herein before described for the reason that the structural strength of the device is not impaired because only one wing is employed around the lower periphery of the shell, and since it is desirable that the cutout portion be as large as possible to facilitate the entry of the object to the interior of the shell.

In Figure 7, there is illustrated a modified form of the object engaging means. In this embodiment, the lower end of the string of tools 16 is threaded to extend downwardly within the interior of the coupling member 48, and is provided with an internally threaded socket at its lower end for receiving the threaded upper end threading die 68. The threading die 68 is disposed in alignment with the axis of the shell 20, and is conical in shape so as to facilitate the entry of the threading member into the upper end of an object 14 should the latter be hollow. It will be understood that upon rotation of the device 10, the threading member 68 will become firmly engaged with an object 14 so as to permit the withdrawal of the latter from the well with the device 10.

While the preferred material of construction of the present invention is steel, it will be understood that the same may be formed of any suitable material. Inasmuch as the object engaging means are carried by the coupling member 48, it will be evident that since the coupling member 48 is detachable from the shell 20, the wings 22, and the transverse wall 42, that these latter mentioned elements may be used with various coupling members and the object engaging means carried thereby so as to increase the use of the same.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents may be resorted to, falling within the scope of the appended claims.

Having described the invention, what is claimed as new is:

1. In a well fishing tool, a vertical tubular shell adapted to be inserted in a well and lowered to a position adjacent the top of an object to be removed from the well, an arcuate wing having an

upper inner end pivoted to shell adjacent the lower end of the shell and about a pivot that is substantially tangential to the shell and at an inclined angle to the longitudinal axis of the shell, said wing being swingable from a retracted position in which the concave side of the wing faces towards the shell and in which position the wing is to be disposed when the shell is lowered into the well to an extended position extending a substantial distance laterally from the periphery of the tubular shell, the lower end of the shell being cut away on one side adjacent the wing, the center of mass of said wing being so disposed that rotation of the shell about its longitudinal axis urges the wing towards its extended position by centrifugal force, said shell having a slot therein accommodating the inner end of said wing, and said pivot being located within the interior of said shell, and said wing being pivoted to the shell about an axis inclined to the horizontal plane.

2. In a well fishing tool, a tubular shell adapted to be inserted in a well and lowered to a position adjacent an object to be removed from the well, means pivoted to shell adjacent the lower end of the latter for engaging and directing an object into the lower end of the shell upon axial rotation of the latter, the pivot for means being substantially tangential to the shell and inclined relative to the longitudinal axis of the shell, a transverse wall in said shell above said means, said transverse wall having a concaved lower surface merging with the inner periphery of said shell and a central aligning opening therethrough.

3. In a well fishing tool, a tubular shell adapted to be inserted in a well and lowered to a position adjacent an object to be removed from the well, means pivoted to shell adjacent the lower end of the latter and about an axis that is substantially tangential to the shell and at an inclined angle to the longitudinal axis of the shell for engaging and directing an object into the lower end of the shell upon axial rotation of the latter, a transverse wall in said shell above said means, said transverse wall having a concaved lower surface merging with the inner periphery of said shell and a central aligning opening therethrough, and means carried at the upper end of the shell in axial alignment with the aligning opening for engaging an object extending upwardly through said aligning opening.

4. The combination of claim 3, wherein said last means comprises a depending, externally threaded member.

5. The combination of claim 3, wherein said last means comprises a depending, externally threaded conical member.

6. The combination of claim 3, wherein said last means comprises a pair of jaws for gripping the upper end of an object.

7. The combination of claim 3, wherein said last means comprises a depending tapered tubular member, and a pair of complementary slip jaws disposed in said tubular member.

8. In a well fishing tool, a tubular shell adapted to be inserted in a well and lowered to a position adjacent an object to be removed from the well, means pivoted to shell adjacent the lower end of the latter for engaging and directing an object into the lower end of the shell upon axial rotation of the latter, a transverse wall in said shell above said means, said transverse wall having a concaved lower surface merging with the inner periphery of said shell and a central aligning opening therethrough, said means including a pair of spaced bosses on said shell having aligned apertures, said shell having a slot extending between the bosses, an arcuate wing having an upper inner end disposed in said slot with an aperture therethrough, a pivot pin removably extending through all of said apertures, and releasable means holding said pin in said apertures.

9. In a well fishing tool, a tubular shell adapted to be inserted in a well and lowered to a position adjacent an object to be removed from the well, means pivoted to shell adjacent the lower end of the latter and about axis that is substantially tangential to the shell and at an inclined angle to the longitudinal axis of the shell for engaging and directing an object into the lower end of the shell upon axial rotation of the latter, a transverse wall in said shell above said means, said transverse wall having a concaved lower surface merging with the inner periphery of said shell and a central aligning opening therethrough, a coupling having an enlarged lower end in releasable engagement with the upper end of the shell and a reduced upper end adapted to secure to the lower end of a string of tools, and means disposed in the coupling in axial alignment with the aligning opening for engaging an object extending upwardly through the opening.

10. In a well fishing tool, a tubular shell adapted to be inserted in a well and lowered to a position adjacent an object to be removed from the well, means pivoted to shell about an axis substantially tangential to the shell and at an inclined angle relative to the shell adjacent the lower end of the latter for engaging and directing an object into the lower end of the shell upon axial rotation of the latter, and means carried at the upper end of the shell in axial alignment therewith for engaging and guiding an object extending upwardly in the shell upon rotation of the latter.
